(57) **CLAIM**

We claim the ornamental design for a tiffany lancaster wrought iron, as shown and described.

DESCRIPTION

FIG. 1 is a perspective view of a tiffany lancaster wrought iron, illustrating a first embodiment thereof, showing our new design;

FIG. 2 is a perspective view thereof, illustrating a second embodiment thereof;

FIG. 3 is a front elevational view of the first embodiment thereof;

FIG. 4 is a rear elevational view of the first embodiment thereof;

FIG. 5 is a left-side elevational view thereof;

FIG. 6 is a right-side elevational view thereof;

FIG. 7 is a top plan view of the first embodiment thereof;

FIG. 8 is a bottom plan view of the first embodiment thereof;

FIG. 9 is a front elevational view of the second embodiment thereof; and,

FIG. 10 is a rear elevational view of the second embodiment thereof.

The broken lines showing a doors and windows in FIGS. 1 and 2 are included for the purpose of illustrating the invention in use, and form no part of the claimed design.
